UNITED STATES PATENT OFFICE.

JOHN HENRY PRICE, OF STOKE-ON-TRENT, ENGLAND, ASSIGNOR TO CAULDON POTTERIES, LTD., OF STOKE-ON-TRENT, ENGLAND, A COMPANY REGISTERED UNDER THE COMPANIES' ACT OF GREAT BRITAIN.

DESIGN FOR A SERVICE PLATE OR LIKE ARTICLE.

Application filed February 9, 1924. Serial No. 8,590. Term of patent 7 years.

To all whom it may concern:

Be it known that I, JOHN H. PRICE, a subject of the King of Great Britain, and a resident of Stoke-on-Trent, England, have invented a new, original, and ornamental Design for a Service Plate or like Article, of which the following is a specification, reference being had to the accompanying drawing, forming part thereof.

The figure represents a plan view of a plate embodying my new design.

I claim:

The ornamental design for a service plate or like article, as shown.

JOHN HENRY PRICE.
